UNITED STATES PATENT OFFICE.

WALTER M. LANGSDORF, OF NEW YORK, N. Y.

DESIGN FOR BACK OF A MIRROR OR SIMILAR ARTICLE.

Application filed November 18, 1926. Serial No. 19,767. Term of patent 3½ years.

To all whom it may concern:

Be it known that I, WALTER M. LANGSDORF, a citizen of the United States, and resident of New York, in the county of New York and State of New York, have invented a new, original, and ornamental Design for Back of a Mirror or Similar Article, of which the following is a specification, reference being had to the accompanying drawing, forming part thereof.

The drawing represents a plan view showing my new ornamental design for the back of a mirror.

I claim:

The ornamental design for the back of a mirror or similar article, as shown.

WALTER M. LANGSDORF.
